UNITED STATES PATENT OFFICE.

ERIC JULIUS PILBLAD AND ARTHUR TOMLINSON, OF LEICESTER, ENGLAND, ASSIGNEES
TO IMPERIAL TYPEWRITER COMPANY, LIMITED, OF LEICESTER, ENGLAND.

FEED-ROLLER OF TYPE-WRITERS.

1,153,567.

Specification of Letters Patent. Patented Sept. 14, 1915.

Application filed July 31, 1914. Serial No. 854,276.

To all whom it may concern:

Be it known that we, ERIC JULIUS PILBLAD and ARTHUR TOMLINSON, subjects, respectively, of the Kings of Sweden and of England, residing at Leicester, England, have invented certain new and useful Improvements in Feed-Rollers of Type-Writers, of which the following is a specification.

10 This invention is for improvements in or relating to the feed-rollers of typewriters and has for its object to provide an improved construction whereby the paper is prevented from crinkling when it is fed backward in the machine. This occurs when the 15 second or auxiliary feed-roller is allowed to turn with the paper.

Accordingly the present invention consists in the combination in a typewriter, with an auxiliary feed-roller of means automatically preventing it from rotation in one direction, whereby the crinkling of the paper above-mentioned is prevented.

The invention may consist in the combination of a typewriter with an auxiliary feed-roller of a pivoted brake-member, which may be a serrated plate bearing against the curved surface of the roller in such manner that the rotation of the roller 30 in one direction thrusts the brake-member away, but rotation in the other direction draws it in and locks the roller against further rotation in that direction.

The brake-member may be a yieldingly-controlled plate having a wedging surface which is held in contact with the roller in such position that it can be drawn in as above described.

Further features of the invention are hereinafter described and the novel details set forth in the claims.

In the accompanying drawings—Figure 1 shows such parts of the typewriter as are necessary for the understanding of the invention in their normal operating position. Fig. 2 shows the parts with the brake-member in operation preventing backward rotation of the auxiliary feed-roller. Fig. 3 is a plan.

50 Like reference letters indicate like parts throughout the drawings.

The platen A around which the paper passes is provided with a paper strap B. Lugs B¹ are provided on the strap B to receive a pivot pin B², on which is hinged a

bracket C which carries the auxiliary feed-roller D pivoted in two projecting arms C¹. This roller is usually made of indiarubber or like material. A slot is provided in the paper strap B and the roller is pressed forward by a spring C³ attached to a lug C² on the bracket C, through this slot on to the platen A, or on to the paper on the platen.

Within the bracket C and pivotally mounted on the pin B² is a brake-member E. This consists of a plate E¹ provided with up-standing flanges E² which are bored to receive the pivot pin B², and the plate E¹ is bent around as at E³, so as to lie against the auxiliary feed-roller D, the face of the part E³ of the brake-member which bears against the roller is provided with serrations E⁴ which increase the grip of the brake-member upon the roller. The plate is so shaped at E³ as to constitute a wedge member, and it is of such length that it cannot swing down freely between the roller D and its own pivot, but it is sufficiently short to be drawn down by the roller on reverse rotation until it firmly wedges the roller against further movement in that direction.

The brake-member E during normal operation lies in contact with the auxiliary feed-roller D at the point F Fig. 1, and the parts are so disposed that the point F lies above the line joining the pivotal axis of the brake-member to the axis D¹ of the roller D; by this disposition the brake is gravity controlled, but if it is desired to arrange it in some other way a spring may be used to hold it yieldingly in contact with the roller so that it operates in the same way as if gravity controlled.

In the normal operation of the machine the platen is turned in the direction indicated by the arrow G, Fig. 1; the auxiliary feed-roller D turns in the direction indicated by the arrow G¹, Fig. 1, and it therefore tends to turn the brake-member E about its pivot so that the part E³ moves upward away from the roller D. When it is desired to feed the paper backward in the machine the platen is turned in the direction indicated by the arrow H, Fig. 2, and the feed-roller is thereupon turned in the direction indicated by the arrow H¹ in Fig. 2. The brake-member is engaged at the point F by the roller D, and this rotation of the roller turns the brake-member E down into the position shown in Fig. 2, and the part having

the serrations E⁴ is thereby pressed against the roller D and locks it against further rotation in that direction.

It will be appreciated that the main feed-
5 roller delivers the paper normally to the auxiliary feed-rollers which then rotate, but when the movement of the paper is reversed, the auxiliary feed - rollers are held stationary and the paper is drawn from them to
10 the main feed-roller, this method of operation prevents crinkling of the paper as already mentioned.

It will be appreciated that the construction hereinbefore described provides a neat
15 and compact mechanism for preventing the reverse rotation of an auxiliary feed-roller but the invention is not limited to the particular construction illustrated since the many modifications may be made without
20 departing from the spirit of the invention as set forth in the appended claims.

What we claim as our invention and desire to secure by Letters Patent is:—

1. In a typewriter the combination of, a
25 platen, an auxiliary feed - roller bearing thereon, a movable brake-member having a wedging surface bearing on the auxiliary feed-roller in such position that it is drawn in by rotation of the roller in one direction, and wedges it against further rotation, and a yielding control maintaining the wedging surface in contact with the auxiliary feed-roller, substantially as set forth.

2. In a typewriter the combination of, a
35 platen, an auxiliary feed - roller bearing thereon, a pivoted brake-member having a wedging surface bearing on the auxiliary feed-roller in such position as to be thrust away therefrom by rotation in one direction
40 and drawn in to hold the roller by movement in the other direction, and a yielding control maintaining the wedging surface in contact with the auxiliary feed-roller, substantially as set forth.

45 3. In a typewriter the combination of, a

platens, an auxiliary feed - roller bearing thereon, a strut pivoted about an axis parallel with the axis of the auxiliary feed-roller and having a wedging face lying against the said roller in such position that it is drawn in by rotation of the roller in one direction and holds it against further rotation, and a yielding-control maintaining the wedging surface in contact with the auxiliary feed-roller, substantially as set forth.

4. In a typewriter the combination of, a
50 platen, an auxiliary feed - roller bearing thereon, a strut pivoted about an axis parallel to the said roller and having a serrated wedging face lying against the roller, the pivotal axis being so disposed that the wedging surface is maintained in position by the weight of the strut, and the strut being of such length that it cannot swing down freely between the auxiliary feed-roller and its own pivot, but is sufficiently short to be drawn down by the said roller on reverse rotation to firmly wedge the roller, substantially as set forth.

5. In a typewriter the combination of, a
55 platen, a main feed-roller, an auxiliary feed-roller on the delivery side of the main feed-roller, a movable brake member having a wedging surface bearing on the auxiliary feed-roller in such position that it is drawn in by rotation of the roller in one direction and wedges it against further rotation, and a yielding control maintaining the wedging surface in contact with the auxiliary feed-roller, substantially as set forth.

In testimony whereof we have signed our names to this specification in the presence of two subscribing witnesses.

ERIC JULIUS PILBLAD.
ARTHUR TOMLINSON.
